UNITED STATES PATENT OFFICE.

HORACE E. WHITNEY, OF CAMBRIDGE, MASSACHUSETTS, ASSIGNOR TO DOVER STAMPING & MANUFACTURING COMPANY, OF PORTLAND, MAINE, A CORPORATION OF MAINE.

TIRE-TUBE TESTER.

1,071,124.

Specification of Letters Patent. Patented Aug. 26, 1913.

Application filed May 17, 1911. Serial No. 627,851.

To all whom it may concern:

Be it known that I, HORACE E. WHITNEY, of Cambridge, in the county of Middlesex and State of Massachusetts, a citizen of the 5 United States, have invented a new and useful Improvement in Tire-Tube Testers, of which the following is a specification.

My invention relates to a tank particularly adapted for testing the inner tubes of 10 automobile tires, and it comprises a tank preferably of the shape shown together with means for holding the tube when the test is being made.

When an inner tube is known to leak it 15 has been the custom to submerge the tube or a portion of the tube partly filled with air in water. When the tube is squeezed the air in escaping will work up through the water and so indicate the point of leakage. The 20 inconvenience of such a course lies chiefly in disposing of the part of the tube which is not being manipulated.

My invention comprises the combination of a tank with means, preferably, adjustable 25 according to the size of the tire, upon which the tube may be hung and over which it may be slid during the testing process, and it will be understood by reference to the drawings in which the preferred form of 30 my device is shown.

Figure 1 is a front elevation of my device. Fig. 2 is a side elevation, and Fig. 3 a longitudinal section.

A is the tank the bottom *a* of which is 35 curved. It sets on four legs *a*¹ and may be of any convenient width, say about twice the diameter of the tube. Upon its rear is riveted a plate B carrying a strap *b* into which is set the holder C for the tire. This 40 holder comprises a vertical or rod portion the lower end of which sets in the socket *b* and is then clamped by the set screw *b*¹. Its upper end is bent to form a hook portion *c*

overhanging the tank. On this hook portion the tube is hung.

To utilize my invention the tube represented in dotted lines at D is partly inflated and is then hung on the hook C, the lower part of its depending portion resting in the tank which is partially filled with water, 50 say to approximately the line E, sufficiently to cover the submerged portion of the tube. The user then squeezes that portion of the tube which is submerged and if he sees no air bubbling up through the water, slides 55 the tube around the hook C to submerge another portion of the tube and repeats the squeezing operation until the weak or poorer portion of the tube is found. He then can apply the patch or otherwise mend the tube. 60 The position of the hook can be adjusted by unscrewing the set screw *b*¹ and raising or lowering the holder C as occasion may require according to the size or diameter of 65 the tire.

The tank shown is comparatively small taking but little storage room in a garage and is convenient in shape. It uses a minimum of water and owing to the fact that the tube holder is separable may be easily 70 packed for shipment. It is especially convenient for private use, although useful for public garages.

What I claim as my invention is:—

The tube tester above described comprising a tank rectangular in cross section and having its bottom curved in vertical plane, in combination with a rod adjustably mounted in vertical position on the side of said tank, the upper end of said rod being 75 bent to form a hook overhanging said tank.

HORACE E. WHITNEY.
